CLAIM

The ornamental design for an automatically actuated
electrical switch for use with an automobile power
system, as shown and described.

DESCRIPTION

FIG. 1 is a front and upper left perspective view of an
automatically actuated electrical switch for use with an
automobile power system showing my new design;
FIG. 2 is a top plan view thereof;
FIG. 3 is a bottom plan view thereof;
FIG. 4 is a left side elevational view thereof;
FIG. 5 is a right side elevational view thereof;
FIG. 6 is a front elevational view thereof; and,
FIG. 7 is a rear elevational view thereof.

FIG. 1

FIG. 2

FIG. 3

FIG. 6

FIG. 7

FIG. 4

FIG. 5
